DESIGN FOR A LIGHTER FOR CIGARETTES OR THE LIKE

Leonard A. Cutrow, Los Angeles, Calif.

Application June 5, 1945, Serial No. 119,908

Term of patent 7 years

(Cl. D48—27)

To all whom it may concern:

Be it known that I, Leonard A. Cutrow, a citizen of the United States, residing at Los Angeles, in the county of Los Angeles, State of California, have invented a new, original, and ornamental Design for a Lighter for Cigarettes or the like, of which the following is a specification, reference being had to the accompanying drawing, forming a part thereof, in which:

Fig. 1 is a perspective view of a lighter for cigarettes, or the like showing my design;

Fig. 2 is a side view of the lighter;

Fig. 3 is an edge view thereof, taken at 3—3 of Fig. 2;

Fig. 4 is a side view of the lighter with the cover in an open position;

Fig. 5 is a top view thereof, taken at 5—5 of Fig. 4, showing the cover open.

I claim:

The ornamental design for a lighter for cigarettes or the like, substantially as shown.

LEONARD A. CUTROW.
